BUILDING BLOCK

Verne Frese, 7265 E. Marginal Way S., Seattle, Wash.

Filed June 10, 1964, Ser. No. 80,352

Term of patent 14 years

(Cl. D18—2)

FIG. 1 is a perspective view of a building block showing my new design.

FIG. 2 is a top plan view of the block.

FIG. 3 is a front elevational view of the block; and FIG. 4 is an end view thereof.

I claim:

The ornamental design for a building block, as shown.
